UNITED STATES PATENT OFFICE.

HENRY W. NAGEL, OF CHICAGO, ILLINOIS, ASSIGNOR OF ONE-HALF TO AUGUST C. RONDA.

LOADING DEVICE.

1,342,456.

Specification of Letters Patent.

Patented June 8, 1920.

Application filed April 23, 1919. Serial No. 292,106.

To all whom it may concern:

Be it known that I, HENRY W. NAGEL, a citizen of Germany, residing at Chicago, in the county of Cook, State of Illinois, have 5 invented certain new and useful Improvements in Loading Devices, of which the following is a specification.

The present invention relates generally to loading devices for handling materials 10 of various kinds and has to do more particularly with devices where the material is conveyed to the delivery point, or points, by gravity. The features of the invention are particularly applicable to locomotive coal- 15 ing stations and the invention will be described in that connection. In the particular embodiment here presented, the coal is received from a pocket into a rotary drum which receives and delivers a charge during 20 each revolution and the charge so delivered is directed to one of two chutes from which it passes to the locomotive tender. Each drum full furnishes a definite amount of coal. A gate for directing the coal into 25 either chute is controlled in its operation by the movement of one of the chutes. The different features and advantages of the invention will be more fully understood upon reference to the following detailed descrip- 30 tion taken in connection with the accompanying drawing while the scope of the invention will be particularly pointed out in the appended claims.

In said drawing, Figure 1 is a vertical 35 section of a portion of a coaling station embodying the features of the present invention; Fig. 2 is a side elevation of the principal parts shown in Fig. 1; Fig. 3 is a perspective view of the drum which receives 40 and delivers the charges of coal; and Fig. 4 is a partial sectional view similar to Fig. 1 of a modified form of the invention. Throughout these views like characters refer to like parts.

45 Referring to the drawing in detail, A designates the coal pocket, B the drum, C the drum frame, D the double outlet spout, E and F the chutes, and G an electric motor for driving the drum.

50 The coal pocket A may be built according to any preferred construction. In the present instance its walls are composed of reinforced concrete. The pocket is located at a sufficient elevation to allow a train to 55 readily pass beneath the chutes E and F

when they are in their elevated positions. The maximum cross section of such a train is indicated by the dotted outlines 10. The pocket A may be supported in any desired way, as for instance, by piers one of which 60 is indicated at 11. The particular way of constructing and supporting the pocket forms no part of my invention and need not be described in further detail. The bottom of the pocket is provided with an outlet 12 through which the coal is adapted to pass by gravity.

The drum B is located directly beneath the opening 12 in the frame C. This frame consists of sides 13, 14, and ends 15, 16, 70 These parts may be castings or they may be built up of sheet steel and angles. In the present instance the sides and ends have flanges 17 which fit against the under side of the pocket A around the opening 12. 75 Threaded rods 18 are positioned in the concrete of the pocket A during the construction of the pocket and when the frame C is put in place these rods extend through openings in the flanges 17 and by means of 80 nuts, threaded on the rods and bearing against the flanges, the sides and ends of the frame C are securely fastened to the pocket A. The sides 13 and 14 of the frame C have curved walls which are concentric 85 with the axis of the drum. When the drum is in place in the casing there is a slight clearance between these sides and the cylindrical wall of the drum. The ends 15 and 16 of the frame C have enlarged portions 90 which are bored out to form bearings 19 and 20 for the stud shafts 21 and 22, respectively, of the drum B. The end 16 is also provided with an extension 23 which forms a support for the motor G. The shaft of 95 the latter is geared to the stud shaft 22 of the drum through suitable gearing including the pinion 24, gear wheel 25 and worm gearing within the casing 26.

The drum B is preferably constructed of 100 sheet steel having ends 27 and 28 joined by a cylindrical wall 29. One side of the cylinder thus formed is cut away so as to provide an opening of substantially the same cross sectional area as the outlet 12 of the 105 pocket A. The stud shafts 21 and 22 extend outward from the ends 27 and 28 respectively. The interior of these ends is in each instance reinforced by a member 30 which serves to strengthen the ends at the 110

points where the stud shafts are attached. If desired these reinforcing members may be integral with the stud shafts. The interior of the cylindrical wall 29 is reinforced by angle irons 31. From the description thus far it will be seen that when the drum rotates, one edge of the opening will be forced into the coal to separate that which is in the pocket from that which is in the 5 drum. In other words, one edge of the opening has to cut its way through the mass of coal. This cutting edge is preferably provided with a toothed casting 33 upon which are located ribs 34 which are positioned so as to fit against the projecting portions of the angles 31. By riveting the ribs to the angles the casting 33 is firmly held in place. Its teeth 35 are provided so as to more readily cut through the coal. 10 When the parts are in operation the drum rotates in the direction indicated by the arrow in Fig. 1.

The sides 13 and 14 of the frame C are provided at their lower edges with flanges 25 36. These flanges provide means for connecting like flanges 37 upon the upper end of the spout D. This spout may be formed of cast metal or may be built up of structural steel as desired. It is provided with 30 an upper portion 38 which has practically the same cross sectional area as the opening in the drum. This portion communicates with two outlets 39 and 40. A gate 41 is pivoted midway between the outlets 39 35 and 40 and in one position it closes the outlet 39 and in its alternate position it closes the outlet 40.

The chutes E and F are respectively pivoted to lugs 42 and 43 extending downward 40 from the spout D. Each chute consists of side walls 44, a bottom 45 and an end 46. The bottom 45 does not extend as far as the sides 44 and consequently leaves an opening 47 through which the coal passes. 45 The weight of the chutes is in each instance counterbalanced. In the case of chute F the counter-weight 48 is connected to a cord 49 which passes over a pulley 50 in a bracket 51 secured to one side of the pocket A. 50 The opposite end of the cord is secured to the end 46 of the chute F as clearly illustrated. An angle 52 secured to the side of the structure serves as a stop for the counter-weight 48. In the case of chute E a cord 55 53 is similarly secured to the end of the chute and passes over a pulley 54 in a bracket 55 upon the inclined side of the pocket. This cord may also be provided with a counter-weight similar to the weight 60 48, but the arrangement of the cord and weight will be obvious and need not be further referred to.

The gate 41 is operated in response to 65 movements of the chute F. This is brought about by securing a gear segment 56 to the

chute and a coöperating gear segment 57 to the gate. The gear segment 57 and the gate are preferably secured to a common pivot rod 58. With this arrangement it will be seen that when chute F is in its lowermost 70 position, gate 41 is in position to close the outlet 39. On the other hand, when chute F is in its uppermost position, gate 41 will close outlet 40.

In the normal condition of the parts the 75 chutes E and F are elevated, the motor G is at rest and the pocket A is provided with a supply of coal. When it is desired to use the device, the locomotive is moved into position so as to bring the tender beneath one 80 of the chutes. The arrangement is such that locomotives on two different tracks may be loaded from the same pocket. If it be assumed that the locomotive is positioned so as to be supplied through chute E, then all 85 that the attendant has to do is to lower the end of the chute from the full line position to the dotted line position of Fig. 1, and start the motor G. For the latter purpose a switch convenient to the chute may be provided. As soon as the motor starts, the drum B begins to rotate and coal which has passed from the pocket into the drum is delivered through the opening of the drum into the spout D. It will be noted that at 95 this time the chute F is in its elevated position and the gate 41 is in its dotted line position. The coal delivered into the spout will then pass out through outlet 39 into the chute E and thence into the locomotive tender. Upon each revolution of the drum a definite amount of coal is taken from the pocket and discharged into the tender. As the drum rotates the teeth 35 crush the lumps of coal as they cut through it and insure a full charge for each revolution. In a commercial installation, the drum would ordinarily make four revolutions a minute and the drum would hold about one ton, thus making a delivery of approximately 100 four tons per minute to the locomotive.

If it be assumed that the locomotive is on the track which would bring it under chute F, then the chute E would be in its elevated position and as soon as chute F was lowered, 115 gate 41 would be moved into the full line position of Fig. 1. Then, as soon as the motor was started, coal would be delivered through outlet 40 into chute F and thence to the locomotive.

In some instances the coal may include 125 many large and hard lumps and in such cases it may be preferable to employ a structure which does not require that the advancing edge of the drum cut through the coal on a definite and fixed line. To meet such a case I provide the structure of Fig. 4 wherein the drum B' receives the coal at a slightly different angle than does the drum B in the structure of the previous figures. 130

In this structure frame C' in which the drum is located is also larger than the frame C which incloses the drum B. The frame C' fits closely against the drum B' on one side 5 so as to provide a slight clearance while on the other side a considerable space is left for the passage of coal which may not enter the drum but be carried around upon its outer surface. The outlet spout D' also differs in shape from the outlet spout D but 10 the arrangement of the chutes E and F and the gearing for operating the gate 41 are the same. The drum B' is the same in construction as the drum B, except that the teeth for cutting through the coal are omitted. In 15 other words, it is the same except that the casting 33 is omitted. In this case the drum is preferably rotated in the direction indicated by the arrow in Fig. 4 which is opposite to the direction in which the drum B is rotated. The gearing for driving the 20 drum B' will therefore require an additional gear wheel in the train so as to give this reversed direction of rotation. The frame C' is secured to the coal pocket A in any suitable 25 way and is located at its outlet 12 so as to receive the coal against the inclined face 60 of the frame. As the coal engages this face it moves downward toward the left, as 30 viewed in Fig. 4, into the drum B' whenever the latter has its open side in position to receive the coal. As the drum rotates the coal within the drum is conveyed around and separated from that upon and adjacent to 35 the inclined face 60. If large lumps of coal are encountered at a time when the drum is practically filled, they will be pressed upward and kept out of the drum. As the drum rotates some of these lumps may be 40 carried on the outer surface of the drum until they have advanced far enough to drop into the passage 61. In such a case they will be mixed with the coal discharged from the drum B' at the time when the open side 45 of the drum reaches a point above the outlet spout D'. If the lumps are too large to enter the passage 61 they will pass out through the opening 62 and fall to the ground or to any receptacle that may be provided to receive 50 them. Ordinarily but few lumps will be encountered which will not enter the passage 61. At the same time that the large lumps are being carried around upon the outer surface of the drum B', small pieces 55 of coal may also be carried around and they will enter the passage 61 and finally drop into the spout D' the same as those pieces which are discharged from the drum. Where the coal is broken up into small pieces or is 60 of a small size when it comes from the mine, the drum B should be used. It is only where the coal contains large lumps that the drum B' and its associated structure is to be employed. With this modified construction the 65 coal is not measured with the same accuracy

as with the structure employing drum B but the measurements will ordinarily be sufficiently accurate because of the small amount of coal which will be carried around on the outer surface of the drum. When the 70 coal has been delivered to the spout D' it will be deposited in the chutes E and F according to the position of gate 41 controlled by the gear segments 56 and 57 just as heretofore described in connection with the 75 structure of Fig. 1. In this modified structure I have shown the chutes E and F somewhat smaller in proportion to the other parts than in Fig. 1 but these may obviously be of any desired size according to the in- 80 tended capacity of the plant.

Although the invention has been described with reference to a construction for handling coal, it is obvious that many of its features might be employed in handling 85 other materials and in feeding them to cars or other receptacles. I, therefore, do not wish to be limited to the particular application herein illustrated but aim to cover the invention in its broad aspect in the appended 90 claims. It will also be obvious that in carrying out my invention certain modifications and alterations may be made in the details of construction and arrangement of parts without departing from the spirit and scope 95 of my invention.

What I claim as new and desire to secure by Letters Patent of the United States, is:

1. A loading device comprising a pocket, a double outlet spout, rotary means for receiving charges of material from said pocket and delivering them to said spout, chutes extending from the spout outlets, one of said chutes being movable, and means responsive to the movements of said movable 100 chute to direct the delivery of the charge to either of said chutes.

2. A loading device comprising a pocket, a delivery spout, a rotary receptacle having an opening in one side through which material is received from said pocket and delivered to said spout as said receptacle rotates, means for allowing material in excess of said charges to be received upon and carried by said receptacle, and means for 105 guiding the excess material to said spout as it passes from said receptacle.

3. A loading device comprising a delivery spout having two outlets, said spout having upper inclosing walls forming a vertical 110 passage and a lower wall forming the bottom of said spout between said outlets, chutes extending from said outlets, one of said chutes being movable, a gate in said spout pivoted adjacent to said lower wall at 115 a point approximately midway between said outlets, said gate when in one extreme position resting at its upper end against one of said upper inclosing walls and when in its other extreme position resting against the 120

130

- opposite upper inclosing wall, and connections between said gate and said movable chute whereby the movement of said movable chute into its lowermost position will 5 set said gate for the delivery of material to said movable chute and the movement of the same chute into its uppermost position will set said gate for the delivery of material to said other chute.
- 10 4. A loading device comprising a pocket, a rotary receptacle having an opening in one side through which material is received and delivered in measured charges as said receptacle rotates, means for allowing material to be received upon and carried by said receptacle in excess of the material within it, and a spout for receiving both the measured and excess material as it comes from said receptacle.
- 15 5. A loading device comprising a rotary receptacle having an opening in one side through which material is received and delivered as the receptacle rotates, a double outlet delivery spout located beneath said receptacle for receiving the material as it is delivered therefrom, and a gate for directing the delivery of the material through either outlet according to its position.
- 20 6. A loading device comprising a rotary receptacle having an opening in one side through which material is received and delivered as the receptacle rotates, a double outlet delivery spout beneath said receptacle for receiving the material as it is delivered therefrom, a gate for directing the material through either outlet according to its position, chutes for receiving said material from said outlets, one of which is movable, and gearing for operating said gate in response to the movements of said movable chute.
- 25 7. A loading device for delivering charges of material, comprising a material pocket having an outlet through which the material is adapted to pass by gravity, a rotary drum having an open side brought intermittently to said outlet to receive material into said drum and operating in other positions to close said outlet, a double outlet spout beneath said drum for receiving charges of material from the latter when its open side is brought into line with said spout, counter-weighted pivoted chutes leading in opposite directions from the outlets of said spout, a pivoted gate in said spout for alternately closing said outlets, and gearing between said gate and one chute for operating said gate in response to the movements of said chute.
- 30 8. A loading device comprising a pocket, a rotary receptacle having an opening in one side through which material is received and discharged as said receptacle rotates, said receptacle being spaced from the outlet of said pocket and positioned to one side of the center of the same, said spacing being sufficient to allow free passage in a horizontal direction of large lumps of material which do not enter said receptacle, an inclosing casing fitting closely to that side of said 70 receptacle which is nearest the center of said outlet and providing a wide delivery passage at the opposite side of said receptacle, and an outlet spout for said casing and passage, said receptacle being rotated in operation so that its upper part moves toward said delivery passage, whereby material in excess of the charge within said receptacle is delivered into said passage and from said passage and receptacle into said outlet spout. 80
9. A loading device comprising a pocket, a rotary receptacle having an opening in one side through which material is received and discharged as said receptacle rotates, said receptacle being spaced below the outlet of said pocket and positioned to one side of the center of the same, said spacing being sufficient to allow free passage in a horizontal direction of large lumps of material which do not enter said receptacle, an inclosing casing fitting closely to that side of said receptacle which is nearest to the center of said outlet and spaced therefrom at its opposite side so as to provide a wide delivery passage, said casing being provided 85 with an opening in its outer wall adjacent to the upper end of said passage through which material may be discharged which is too large for said passage, and an outlet spout at the bottom of said casing and passage, said receptacle being rotated in operation so that its upper part moves toward said passage, whereby material in excess of the charge in said receptacle may be delivered either out through said opening or 90 into said passage and thence through said outlet spout.
10. A loading device comprising a pocket, a rotary receptacle having an opening in one side through which material is received and discharged as said receptacle rotates, said receptacle being spaced from the outlet to said pocket below the same, far enough to allow the free passage in a horizontal direction of large lumps of material which 110 do not enter said receptacle, an inclosing casing for said receptacle having an opening in horizontal alinement with the space between said pocket outlet and said receptacle, and an outlet spout at the bottom of 115 said casing, said receptacle being rotated in operation so that its upper part moves toward said opening.
11. A loading device comprising a pocket, a rotary receptacle having an opening in one side through which material is received and discharged as said receptacle rotates, said receptacle being spaced from and below the outlet of said pocket far enough to allow the free passage in a horizontal direction of 120
- 125

large lumps of material which do not enter said receptacle, an inclosing casing for said receptacle fitting close to it at one side and spaced therefrom at the other side to provide a passage, and an outlet spout at the bottom of said casing and passage, said receptacle being rotated in operation so that its upper part moves toward said passage, whereby material in excess of the charge 10 within said receptacle is delivered to said passage and thence to said spout.

12. A loading device comprising a pocket, a rotary receptacle having an opening in one side through which material is received 15 and discharged as said receptacle rotates, said receptacle being spaced from and below the outlet of said pocket, far enough to allow the free passage in a horizontal direction of large lumps of material which do

not enter said receptacle, an inclosing casing for said receptacle fitting close to it at one side and spaced from it at the other side so as to provide a passage, said casing being provided with an opening in its outer wall adjacent to the upper end of said passage through which material may be discharged that is too large for said passage, and an outlet spout at the bottom of said casing and passage, said receptacle being rotated in operation so that its upper part 20 moves toward said opening, whereby material in excess of the charge in said receptacle may be delivered either out through said opening or into said passage and thence through said spout.

In witness whereof I hereunto subscribe my name this 18th day of April, 1919.

HENRY W. NAGEL.
